SERN MADSEN, OF CLINTON, IOWA, ASSIGNOR TO CURTIS COMPANIES, INCORPORATED, OF CLINTON, IOWA

SASH LOCK FOR CASEMENT SASH

Application filed February 18, 1929. Serial No. 340,967.

The object of this invention is to provide an improved locking device for casement sash.

A further object of the invention is to provide an improved sash lock, which is operable from the interior of a building and is provided with two coacting parts adapted for interengagement for drawing and holding a swinging or casement sash in closed position.

Another object of the invention is to provide a casement sash lock which may be operated by means of a rotatable wrench capable of being inserted through an opening in a screen located interiorly of the sash.

Still another object of the invention is to provide a lock for casement sash, which is simple and economical to produce and efficient in operation.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a horizontal section through a window frame having a casement sash and a screen mounted therein and equipped with my improved locking device, a crank-operated wrench being shown in this view.

Figure 2 is a detail horizontal section illustrating one of the locks in position for practical use for holding the sash in closed position, a headed wrench being illustrated in this view.

Figure 3 is a vertical section on the line 3—3 of Figure 2.

Figure 4 is a perspective view illustrating the various parts of the lock detached from each other prior to installation.

Figure 5 is a perspective view of the housing employed, from the opposite end to that shown in Figure 4.

My improved locking device is designed for use with a swinging or casement sash A, which is adapted to be mounted in a window frame having spaced jambs 10 and 11. The sash A is provided with stiles 12 and 13 and

the stile 12 is hingedly connected to the jamb 10 by means of hinges 14, while the stile 13 is adapted to fit into an outwardly opening rabbet 15 in the jamb 11.

In connection with casement windows it is quite customary to mount window screens interiorly of the sash, or in other words, in rabbits or seats formed at the inner margins of the jambs 10 and 11, as shown. I have here shown a screen B mounted in the window frame, said screen including stiles 16 and 17 spaced inwardly from the stiles of the sash.

Casement sash of the type in question are often provided with mechanical devices for adjusting and holding them to any desired degree of opening and some of such adjusting devices are operable through a screen such as B.

However, difficulty has been encountered in drawing the sash to a tightly closed position, particularly when the sash stiles are somewhat warped or where they fit so closely as to bind in their seats or in cases where snugly fitting weather stripping is employed.

Furthermore, in installations where a screen such as B is mounted interiorly of the sash A, it is frequently necessary to unfasten and open the screen in order to get at the locking devices. This not only requires considerable time and trouble, but also permits the entrance of flies and insects to the building and is apt to result in tearing, wrinkling, or otherwise disturbing lace curtains, drapes, or shades, which may be mounted on the window.

It is to overcome these difficulties that I have designed my improved locking device, which is operable through a screen such as B from the interior of the building and is capable of engaging a sash such as A and drawing it in to tightly closed position and holding it in such position. This operation preferably is carried out through the use of a wrench or similar tool adapted to be inserted through an opening in the screen frame.

In the exercise of my invention I employ a housing 18, which is adapted to be mounted on the face of a jamb member such as 11 adjacent to the free marginal portion of a case-

ment sash such as A. The housing 18 may be held in place by means of screws 19 extended through apertured ears 20.

The housing 18 is formed with a longitudinal bore 21 arranged horizontally and the outer end portion of said bore is restricted in diameter by means of a shoulder 22.

A screw bolt 23 is provided and is formed with relatively rugged or coarse threads and with an attenuated outer end portion 24.

10 The screw bolt 23 is formed with a cylindrical head 25, which is fitted to the bore 21 of the housing 18. The screw portion 23 of the bolt is adapted to extend through the restricted outer end of the bore, but the shoulder 22 prevents the head 25 from passing therethrough.

20 The head 25 of the screw bolt is formed with an angular socket 26 and said bolt is adapted to be rotated by means of a wrench or similar tool 27 having at one end, an angular portion 28 corresponding in cross section to the shape of the socket.

25 The wrench 27 is adapted to be inserted through a bore 29 in the rail 17 of the screen 20 for engagement with the socket of the screw bolt.

30 Any suitable means may be employed for manually turning the wrench 27 and for this purpose I have shown, in Figures 2, 3 and 4, a flattened head 30 on the outer end of the wrench.

In Figure 1, is shown a wrench having a crank 31 on its end for rotating it.

35 The housing 18 has a relatively flat face adapted to contact with the face of the jamb 11 and this face is formed with a longitudinal recess 32 preferably terminating in a rabbet 33 in the outer end portion of the housing.

40 A keeper plate 34 is provided, which is adapted to be mounted in the recess 32 of the housing before the housing is installed and said keeper plate has at its outer end, a short flange 35 adapted to engage in the rabbet 33.

45 At its opposite end the keeper plate 34 is formed with a flange 36, which preferably corresponds in shape to the cross sectional shape of the housing 18. The flange 36 is adapted to contact with the inner end of the housing 18 and is formed with a circular opening 37 in alignment with the bore 21 thereof.

50 The keeper plate 34 is held in place in the recess 32 of the housing and its flanges 35 and 36 prevent accidental displacement therefrom.

55 The flange 36 of the keeper plate serves to prevent withdrawal of the screw bolt from the housing as its opening 37 is of less diameter than the head 25 of the bolt and yet, sufficiently large to permit the entrance of the angular portion 28 of the wrench or operating tool.

60 On the stile 13 of the sash A, or in other words, on the stile which is free relative to

the window frame, is mounted a nut member 38, which is formed with an internally threaded bore 39 adapted to receive the threaded portion of the screw bolt.

The nut member 38 may be held in place on the stile 13 by means of screws 40 and the stile preferably is formed with a recess 41 back of said nut member to receive the end of the screw bolt 23.

If desired, an apertured face plate 42 may 75 be mounted over the bore 29 of the screen stile 17 to give it a finished appearance.

When a casement sash is equipped with my improved locking device, the nut member 38 may be caused to be engaged by the screw 80 bolt 23 before the sash has been drawn to tightly closed position, as illustrated in Figure 1. This is accomplished by inserting the tool or wrench 27 through the bore of the screen, causing its angular end 28 to enter the socket 26 of the screw bolt, and rotating the tool to force the point of the screw bolt into the threaded bore 39 of the nut member 38.

Continued rotation of the tool 27, either by 90 means of a head 30 or a crank 31, in a clockwise direction, will cause the sash A to be drawn inwardly to completely closed position and thereafter, the interengagement of the screw bolt and nut member will serve 95 to hold the sash in tightly closed position.

The wrench or tool 27 may, of course, be withdrawn and removed until it is again required for rotating the screw bolt.

The attenuated end 24 of the screw bolt 100 is provided to facilitate easy entrance of the screw bolt to the bore of the nut member.

It is obvious that one or more of the locking devices may be employed on each sash and the number and location of these locking 105 devices will be governed by the size and condition of the sash.

It should be noted that when the screw bolt 23 is not in engagement with the nut member 38, it is capable of a sliding movement in the housing 18, which movement is limited in one direction by engagement of the head 25 with the shoulder 22 and in the opposite direction by engagement with the flange 36 of the keeper. This provides 110 against damage to the screw bolt or to the nut member, which might occur through slamming or forcible closure of the sash, causing these two members to be brought 115 forcibly together.

One of the advantages of this locking device is that it can begin to operate before the sash is drawn to fully closed position, or in other words, it has the function of pulling the sash to tightly closed position and then holding it there securely. It is obvious that any desired length of draw, through operation of the screw bolt, can be provided by varying the length of the screw.

This lock is also efficient in that it may be 130

applied at both the upper and lower portions of the sash to securely close and lock the sash, which may be warped or otherwise poorly formed or fitted.

5 Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

15 1. A locking device for a casement sash, comprising a housing mounted on the window jamb, a screw bolt having a head arranged for rotation and for sliding movement in the housing and also having a threaded portion adapted to be projected therefrom, a keeper plate confined between the housing and window jamb and having a portion overlying one end of the housing to prevent removal of the screw bolt therefrom, and a nut member carried by the sash and adapted to engage the threaded portion of the screw bolt.

20 2. A locking device for a sash mounted for movement relative to another member, comprising a housing mounted on said other member, a screw bolt loosely mounted in said housing, said housing being formed with a longitudinal recess on that face adjacent the said other member and also formed with a rabbet on that end remote from the movable sash, a keeper plate mounted in said recess and having a flange at one end overlying the end of the housing to prevent removal of the bolt therefrom, said bolt having a threaded portion projected through said flange, said plate being formed at its opposite end with a short flange seated in said rabbet to retain the plate relative to the housing, and a nut member carried by the sash and adapted to engage the threaded portion of the screw bolt.
